Patented Mar. 30, 1915.

UNITED STATES PATENT OFFICE.

JOHN H. WAITE, OF BROCKTON, MASSACHUSETTS.

METHOD OF MANUFACTURING BOOTS AND SHOES.

1,133,766.

Specification of Letters Patent. Patented Mar. 30, 1915.

Application filed October 13, 1910. Serial No. 586,841.

To all whom it may concern:

Be it known that I, JOHN H. WAITE, a citizen of the United States, residing at Brockton, in the county of Plymouth and State of Massachusetts, have invented a new and useful Method of Manufacturing Boots and Shoes, of which the following is a specification.

The principal objects of this invention are to provide a simple, convenient, and inexpensive method of making a shoe having means for efficiently supporting a fallen arch, and also of such a nature that it will tend to prevent the falling of the arch of a normal foot, and at the same time having all the flexibility of a Goodyear or hand-sewed article at the front and along the outer side but having a relatively firm shank.

The principal cause of the recent development of fallen arches is the constant cheapening of the shoes, and particularly of the shanks thereof. On account of the construction of this part with the main supporting element concealed, it can be cheapened very easily without detection and this has been done to such a degree in recent years that even the better classes of shoes have been materially weakened.

This invention provides for strengthening this part of the shoe without materially increasing the cost. It may be remarked also that another cause of this difficulty is the almost universal demand for light hand-sewed or Goodyear shoes. By this invention, the advantages thereof are secured without danger of weakening the arches, and in fact with an accompanying means for supporting them.

Reference is to be had to the accompanying drawings in which,

Figure 1 is the bottom plan view of part of a last with an insole thereon ready for lasting and broken away: Fig. 2 is a bottom plan view of the shoe constructed in accordance with this invention, with parts broken away to show interior construction: Fig. 3 is a side elevation of a portion of the shoe shown in Fig. 2: and Fig. 4 is a transverse sectional view of a complete shoe on the line 4—4 of Fig. 2.

The last A is in general of the usual construction, but the metallic heel plate A' is provided with an extension A² nearly half the width of the shank of the shoe and extending along the same on the inner side toward the toe, terminating at the inside ball

of the last. The purpose of this will be set forth hereinafter.

In the manufacture of a boot or shoe according to this invention the insole 9 after being properly channeled from the outside corner of the heel to the inside ball is placed on the last A, with an extension piece 15 on the inside shank, and temporarily tacked in position. Then the upper or vamp 8 is fastened to the last as in the ordinary method of lasting. The edges of the vamp are temporarily tacked down from the outside of the heel at 11 around the toe and back on the inner side to the front end of the extension A². These tacks are not shown as they are pulled out later as the shoe is welted. However, the welt 13 is sewed to the upper and insole by stitches 13^a from the outer front corner of the heel at 11 around to the front end of the shank at the inside ball of the shoe, that is to the front of the projection A². Then a reinforcing piece 10 which is heavier and wider than the welt is placed along the outside of the edge of the vamp along the shank from the front of the heel to the end of the welt to cover the projection A². Permanent tacks 12 are applied throughout the length of this reinforcing piece making the edge uniform in thickness. These tacks pass through and hold the reinforcing piece 10, their points meeting the metal surface beneath and being clenched under so that they firmly hold the insole to the edge of the vamp also. This line of tacks extends around the rear and other side of the heel also. After this the usual shank piece is put in and the outsole laid and rounded. Then the outsole is Goodyear stitched in the usual way from the heel at 11 around the toe and back on the inner side to the rear end of the reinforcing piece 10, or it can be hand-sewed if desired. This stitching gives more flexibility to these parts than to the rest of the shoe. This having been accomplished, the shoe is taken off the last and preferably placed in a Standard screw machine by which screws 12^a are applied going through the outsole, reinforcing piece 10, upper or vamp 8 and insole 9 so as to make the shoe firm and solid at this point. These screws extend throughout the length of the reinforcing piece. This makes the shoe firm and solid along this reinforcing strip and much more rigid than around the rest of the sole. After this the shoe is put through

- the other operations usual in finishing a shoe. By thus fastening the outsole at this point through the insole so as to hold the outsole, reinforcing strip 10, upper or vamp and insole firmly together, the shoe is given at this point a substantial construction and rigidity that cannot be obtained simply by extending the welt around through this space and sewing it in the usual manner.
- 10 The heel may be clinch-nailed in the usual way, or if it is desired to do away with this operation, it can easily be operated upon by the McKay machine or the Standard screw while the shoe is in that machine.
- 15 By the above mentioned procedure, it will be seen that a very strong construction is secured along the inside of the shank, although the flexibility of the front part of the sole and the outside of the shank secured 20 by the Goodyear or hand sewing process is not lost. If desired, however, the outside of the shank may be strengthened also by the McKay machine or Standard screw.
- The object of the reinforcing strip 10 is 25 twofold; namely, first, it constitutes a continuation of the welt, making the edge of the inside shank the same thickness as the outside shank; second and chiefly, a wider and finer piece of leather can be used at this point.
- 30 The insole 9 consists of a piece of sole-leather of the usual shape, except that extending along the inner side of the same, all along that part which comes over the metallic extension A² on the heel plate, there is a 35 projecting piece 15, which, when the shoe is made, projects up just on the inside of the inner lining thereof. In that position it serves to support the inside part of the 40 foot. Thus, a permanent support is provided, one which will not become loosened in wear or get out of position, as it is integrally connected with the insole itself. This projection is skived off at the edge so 45 as gradually to approach a feather edge. Its presence does not necessarily affect the manner in which the shoe is manufactured. As will be seen from Fig. 3, it preferably is of such shape and size as to overlap the 50 counter 16 at the end. Therefore, the counter assists in holding it in position inside the shoe.
- 55 Although I have illustrated and described a preferred way of carrying out the invention, I am aware of the fact that many modifications can be made therein by any person skilled in the art without departing from the scope of the invention as expressed in the claims. Therefore, I do not wish to be limited to the precise order of steps herein described, but—

What I do claim is,—

1. The method of making boots and shoes which comprises placing a vamp and insole on a last, temporarily fastening the edge of

the vamp to the insole from a point near the heel on the outer side around to the toe and back to the ball only on the inner side, permanently fastening the edge of the vamp to the insole from the ball on the inner side 70 along the shank to the heel, stitching the vamp to the insole where it has been temporarily fastened to the insole from said permanent fastening to the heel on the outer side, and firmly securing an outsole to the 75 edge of the vamp and insole along the inner side of the shank.

2. The method of making boots and shoes which comprises placing a vamp and insole on a last, temporarily fastening the edge of 80 the vamp to the insole from a point near the heel on the outer side around to the toe and back to the ball on the inner side, providing a welt extending from a point near the heel on the outer side of the shoe around the 85 forepart to the ball on the inner side, providing a reinforcement heavier than the welt along the inner side of the shank from the end of the welt, permanently fastening the edge of the vamp to the insole and reinforcement from the ball on the inner side 90 along the shank to the heel while on the last, sewing the vamp and welt to the insole where the vamp has been temporarily fastened to the insole, and firmly securing an 95 outsole to the edge of the vamp along the inside of the shank.

3. The method of making boots and shoes which comprises placing a vamp and insole on a last, temporarily fastening the edge of 100 the vamp to the last from a point near the heel on the outer side around to the toe and back to the ball only on the inner side, sewing the vamp and a welt to the insole where the vamp has been temporarily fastened to 105 the last, applying an outsole, sewing the outsole to the welt from the outside of the heel to the ball on the inner side, removing the incomplete boot or shoe from the last, and firmly securing the insole and outsole to the 110 edge of the vamp along the inside of the shank.

4. The method of making boots and shoes which comprises placing on a last a vamp and an insole having a projection extending beyond the inner edge of the shank inside the vamp, sewing the edge of the vamp and a welt to the insole from a point near the heel on the outer side around to the toe and back to the ball only on the inner side, 115 flexibly sewing an outsole to the welt from the inside ball to the heel on the outer side, removing the incomplete boot or shoe from the last, and permanently securing the outsole to the edge of the vamp along the inner side of the shank between the insole proper and projection.

5. The method of making boots and shoes which comprises placing an insole and vamp on a last, placing thereon a welt from 120

the outside front corner of the heel around to the ball on the inside, securing together the insole, vamp and welt throughout the length of the welt, placing a reinforcing piece, heavier and wider than the welt, along the inside shank over the edge of the vamp, nailing it firmly to the vamp and insole, securing an outsole to the welt, removing the boot or shoe from the last, and securing the outsole, reinforcing piece, vamp,

and insole together throughout the length of the reinforcing piece.

In testimony whereof I have hereunto set my hand, in the presence of two subscribing witnesses.

JOHN H. WAITE.
